EP	2365831	9/2011

Primary Examiner — Jennifer L Watkins*(74) Attorney, Agent, or Firm* — Avery Dennison Corporation(57) **CLAIM**

The ornamental design for a catheter dressing, as shown and described.

DESCRIPTION

FIG. 1 is an isometric view of the catheter dressing;
 FIG. 2 is a front of FIG. 1;
 FIG. 3 is a back view of FIG. 1;
 FIG. 4 is a left view of FIG. 1;
 FIG. 5 is a right view of FIG. 1;
 FIG. 6 is a top view of FIG. 1; and,
 FIG. 7 is a bottom view of FIG. 1.
